ATTORNEY

UNITED STATES PATENT OFFICE.

NELSON L. JACOBUS, OF GARDEN CITY ESTATES, NEW YORK.

NAME PLATE OR THE LIKE AND PROCESS FOR MAKING SAME.

Application filed March 30, 1923. Serial No. 628,719.

To all whom it may concern:

Be it known that I, NELSON L. JACOBUS, a citizen of the United States, and a resident of Garden City Estates, in the county of 5 Nassau and State of New York, have invented certain new and useful Improvements in Name Plates or the like and Processes for Making Same, of which the following is a specification.

10 The present invention relates generally to a name plate or the like and the process of making it, for an article that is subject to the action of an acid. The specific article used as an illustration of the invention is 15 an automobile battery containing sulphuric acid.

The main object and feature of the invention is to produce a name plate or the like having raised characters or design which 20 will be resistant to the sulphuric acid of the battery so that it will not be eaten away in the process of use.

In the accompanying drawings the invention is illustrated in a preferred and concrete form in which—

Figs. 1, 2 and 3 are plan views of a sheet of material showing some of the steps in producing the name plate of the invention.

Fig. 4 is a sectional view through the 30 finished name plate.

As is well known automobile batteries contain sulphuric acid to which the plate must be resistant and as is equally well known the raised effect of name plates is 35 conveniently obtained by an etching process and the plate must therefore be susceptible to the action of an etching acid other than sulphuric acid. Lead is resistant to sulphuric acid but is susceptible to the action 40 of nitric acid. Lead in sheet form, on account of its softness is extremely difficult to manipulate, but I have found that by using an alloy of lead such as antimonial lead sufficient stability is imparted to the 45 lead sheet to render it suitable for manipulation.

I take a sheet of antimonial lead, with a slight admixture of tin to relieve the extreme dullness of the material, such as sheet 50 1 and upon it I print or lithograph a solid

design 2. It will be evident that this design may be lettering, pictures or arbitrary symbols. The design thus produced is powdered with asphaltum as indicated at 3 while the ink is wet and the sheet is subjected to heat so as to melt the asphaltum and to merge them with the ink and the whole is baked thereby hardening the design 4. The design thus obtained is resistant to 55 nitric acid as well as to sulphuric acid, but the unprotected portion of the plate is 60 susceptible to the action of nitric acid although resistant to sulphuric acid. The plate is now dipped slightly in nitric acid thereby reducing the thickness of the plate 65 except at the protected parts 4, which latter consequently become raised. The back of the plate may be covered with a protective acid resisting compound, indicated at 5, and the front face of the plate may be finished 70 by varnishing, or lacquering.

I claim:

1. The process of producing a name plate for an article that is subject to the action of an acid which consists in applying, to a 75 sheet of material having the characteristic of resisting the action of the acid to which the article is subject and of not resisting the action of an etching acid other than the first-mentioned acid, a design which will resist the action of both acids, and then subjecting the sheet to the action of said other etching acid, thereby producing a sheet carrying a raised design both the sheet and the design being resistant to the first-mentioned acid.

2. As a new article of manufacture an etched name plate for an article that is subject to the action of an acid composed of 80 a material having the characteristic of resisting the action of the acid to which the article is subject and of not resisting the action of an etching acid other than the first-mentioned acid, said plate having a raised design capable of resisting the action of 85 both acids.

3. The process of producing a name plate for batteries which consists in applying, to a sheet of an alloy of lead, a design which 100 will resist the action of the acid of the bat-

tery and the action of an etching acid other than that of the battery, and then subjecting the sheet to the action of said other etching acid.

5 4. As a new article of manufacture a name plate for batteries consisting of an etched sheet of alloy of lead, said name plate hav-

ing a raised design capable of resisting the action of the acid of the battery as well as the action of the acid used to etch the plate. ¹⁰

Signed at Brooklyn, in the county of Kings and State of New York, this 24 day of Mar., 1923.

NELSON L. JACOBUS.
